UNITED STATES PATENT OFFICE.

HAROLD H. BEVERAGE, OF RIVERHEAD, NEW YORK, ASSIGNEE TO GENERAL ELECTRIC COMPANY, A CORPORATION OF NEW YORK.

RADIORECEIVING SYSTEM.

Application filed May 25, 1921. Serial No. 472,581.

To all whom it may concern:

Be it known that I, HAROLD H. BEVERAGE, a citizen of the United States, residing at Riverhead, in the county of Suffolk, State 5 of New York, have invented certain new and useful Improvements in Radioreceiving Systems, of which the following is a specification.

My present invention relates to radio receiving systems, and more particularly to 10 means for preventing interference in such systems by waves of a wave length in the neighborhood of that of the waves which are to be received and which are traveling in 15 the same direction as the waves to be received.

In my copending application, Serial No. 372,933, filed April 10, 1920, issued on June 7, 1921, as Patent No. 1,381,089, I have described an improved form of unidirectional antenna by means of which signals coming 20 from a given direction may be readily received and applied to the receiving apparatus to the exclusion of signals coming from 25 the opposite direction. In some cases, however, it will be desirable to be able to receive signals coming from the desired direction when there are also present in the antenna strong currents produced by signaling waves coming from the same direction 30 as that of the desired signals and produced by waves of a wave length near that of the desired signal waves and produced by transmitting stations much nearer to the receiving 35 station than the transmitting station from which it is desired to receive signals.

The object of my present invention is to provide means for permitting of the desired 40 reception in a case such as that referred to where the ordinary tuning customarily employed in the receiving circuit will not offer a high enough degree of selectivity to effectively eliminate the interference of signaling waves. The unidirectional antenna 45 which I have described in my application referred to above is preferably untuned so that it offers no discriminating selectivity between the desired signaling waves and interfering waves. In order to provide the desired selectivity and prevent the interfering waves from being impressed upon the receiving apparatus I provide in conjunction with the circuits whereby the desired signaling currents are impressed upon the receiving apparatus, one or more resonant cir-

cuits tuned to the frequency of the interfering waves and arranged in such a way as to form what I term "interference shunts" for absorbing currents produced by the interfering waves, and thus preventing these 60 currents from being impressed upon the receiving apparatus.

The novel features which I believe to be characteristic of my invention are set forth in the appended claims. My invention itself, 65 however, both as to its organization and method of operation will be best understood by reference to the following description taken in connection with the accompanying drawings in which Figs. 1, 2 and 3 70 respectively show three different circuit arrangements, whereby my invention may be carried into effect; Fig. 4 is a diagrammatic representation of a circuit which is the equivalent of the circuit of Fig. 3; and Fig. 75 5 is a representation of tuning curves which may be obtained in the receiving system under different conditions of operation.

As indicated in the drawings, I employ a long horizontal antenna which is preferably 80 made up of two parallel conductors 1 and 2 which are grounded at the ends 3 and 4. Currents received upon this antenna by signaling waves traveling through the ether from the end 4 toward the end 3 will be of 85 substantially zero value at the end 4, and will increase to a maximum value at end 3. On the other hand, currents produced in the antenna by ether waves traveling from the end 3 to the end 4 will be of substantially 90 zero value at the end 3 and will be of a maximum value at the end 4. If, therefore, it is desired to receive signaling waves traveling from the end 4 toward the end 3, the 95 signaling currents produced in the antenna at the end 3 may be impressed upon the receiving apparatus without any interference from currents produced by waves traveling in the opposite direction.

It may not, however, be convenient to locate the receiving apparatus at the end 3 of the antenna, in fact, for reasons which it is unnecessary to set forth in detail, it may be desirable to locate the receiving apparatus at the opposite end. In order to permit of 100 such location of the receiving apparatus the ground connection at the end 3 may be made through the primary 5 of the transformer, the secondary 6 of which has its terminals connected respectively with conductors 1 and 110

2. The conductors 1 and 2 will then serve as a transmission line for transmitting the desired signaling currents from the end 3 to the opposite end. The conductors 1 and 2 thus form the two sides of a transmission line in which the desired signaling currents will flow in opposite directions.

The middle point of transformer secondary 6 is connected to ground at 3, and at 10 the opposite end of the antenna the middle point of the primary winding 7 by means of which the desired signaling currents will be impressed upon the receiving apparatus, is also connected to ground. By reason of 15 this connection currents produced in the antenna by waves traveling from the end 3 toward the end 4 and which flow in the same direction through conductors 1 and 2, will be divided equally between the two halves 20 of the primary 7 and will produce no effect in the secondary 8. If the ground connection at 4 is made through a resistance 9 having a value substantially equal to the surge impedance of the antenna, there will 25 be no reflection of the signaling currents flowing to ground at 4. These currents will then produce no interference with the reception of the desired signaling currents transmitted over the conductors 1 and 2 of 30 the transmission line.

This arrangement, however, will not offer any selectivity between currents produced in the antenna by waves traveling in the same direction as the desired signaling 35 waves. If it happens that there is a transmitting station located much nearer the receiving station than the transmitting station from which the desired signals are to be received and this near-by transmitting 40 station is operating at a wave length in the neighborhood of that of the desired signaling waves, it will be difficult to eliminate the interference from the near-by station by means of the usual tuning circuits 45 employed with the ordinary receiving apparatus. The actual receiving apparatus employed, which I have indicated merely by the rectangle 10 may be of any desired type. In order to avoid such interference 50 I provide a resonant circuit made up of inductance 11 and capacity 12 which is connected in shunt to the primary 7 and which is tuned to the frequency of the interfering waves. The impedance of this shunt circuit 55 to the interfering currents will be so low in comparison with the impedance of the primary 7 that the effect of these interfering currents in the secondary 8 will be substantially eliminated.

60 The nature of the results which are obtained by the arrangement which I have described is indicated by the tuning curve shown in Fig. 5, which illustrates results which have been obtained under actual operating conditions. The tuning curve A re-

resents an actual tuning curve obtained in the receiving apparatus upon signals of a wave length of 14,200 meters without any interference shunt and with a near-by station operating at a wave length of 13,900 meters. 70 When an interference shunt tuned to the 13,900 meter wave length was employed the left-hand side of the tuning curve was shifted to the full line curve B. By using a second interference shunt 13 tuned to a 75 wave length of 14,500 meters the right-hand side of the tuning curve is shifted to the dotted line C. Thus it will be seen that by the use of an interference shunt in the manner described it is possible to eliminate all 80 effect in the receiving apparatus of interfering waves differing in frequency from the desired signaling waves by only 300 meters without producing any appreciable weakening of the desired signaling currents. 85

An interference shunt such as I have described may in some cases be more effectively employed in a bridge circuit such, for example, as that shown in Fig. 2 of the drawing. In this case the two halves 90 of the winding 7 form two arms of the bridge, the interference shunt made of inductance 14 and capacity 15 forms the third arm, and variable resistance 16 forms the fourth arm. This bridge circuit may be 95 balanced by tuning the shunt to the interfering wave and then adjusting the resistance 16 until the interfering signal disappears. The points 17 and 18 to which the receiving apparatus 10 is connected will 100 then be at equipotential points with respect to the interfering wave and the interference will be eliminated. The bridge, however, will not be balanced for the desired signals and the points 17 and 18 will not be at 105 the same potential with respect to the desired signaling waves.

In Fig. 3 I have indicated another bridge arrangement in which two interference shunts are employed which are tuned for 110 interfering frequencies above and below that of the desired signals. In this case the arms 19 and 20 of the bridge are each made up of two parallel interference shunts 21 and 22, while the other two arms of the bridge 115 are formed by resistances 23 and 24. When the interference shunts are tuned to the two frequencies, one above and one below the desired signals, the points 25 and 26 to which the receiving apparatus is connected 120 will be equipotential points with respect to signaling waves of the two frequencies for which the interference shunts are tuned. The bridge, however, will not be balanced for the desired signals and these signals 125 will consequently be impressed upon the receiving apparatus without interference from the interfering waves.

If we assume that the interference shunts 21 are tuned to a frequency slightly above 130

that of the desired signals, then the resultant impedance of the shunts 21 for the desired signals will be inductive and if the shunts 22 are tuned to a frequency slightly below 5 that of the desired signals the resulting impedance of the shunts 22 for the desired signals will be capacitive. If the constants are properly chosen the inductive reactance of the shunts 21 will tune to the capacitive re-

10 actance of the shunts 22 for the signaling frequency. In Fig. 4 I have indicated the equivalent circuit which would then be formed for the desired signaling frequency. In this circuit, it will be seen, the two arms

15 19 and 20 of the bridge form two substantially infinite impedance traps for the signaling frequency. The result therefore is the same as though the desired signaling currents were impressed upon the receiving 20 apparatus through the resistances 23 and 24.

It will be apparent that the same result may be obtained in the arrangement shown in Fig. 1 if the two interference shunts indicated are tuned in the manner described, 25 that is, these two shunts together form a frequency trap of substantially infinite impedance for the signaling frequency and the use of the interference shunts will in no way weaken the strength of the desired signaling 30 currents.

While I have shown and described the preferred embodiments of my invention, it will be apparent that my invention is by no means limited to the exact circuit arrangements shown, but that many modifications therein may be made without departing from the scope of my invention as set forth in the appended claims. For example, while I have indicated the receiving apparatus as 40 being located at the end of the antenna nearest the transmitting station from which signals are to be received, my invention may equally well be employed when the receiving apparatus is located either at the other end 45 of the antenna or at some intermediate point.

What I claim as new and desire to secure by Letters Patent of the United States, is:—

1. The combination in a radio receiving 50 system of an aperiodic horizontal receiving antenna, a receiving apparatus, means for impressing upon said receiving apparatus desired signaling currents produced in said antenna by waves traveling in a given direction, and means for preventing currents produced in said antenna by waves of a frequency near that of the desired waves and traveling in the same direction as the desired waves from being impressed upon said 55 receiving apparatus.

2. The combination in a radio receiving 60 system of an aperiodic horizontal receiving antenna, a receiving apparatus, means for impressing upon said receiving apparatus desired signaling currents produced in said

antenna by waves traveling in a given direction and a resonant circuit which is tuned to a different frequency from that of the desired waves for preventing currents produced in said antenna by waves of a frequency near that of the desired waves and traveling in the same direction as the desired waves from being impressed upon said receiving apparatus. 70

3. The combination in a radio receiving 75 system of an aperiodic horizontal receiving antenna, a receiving apparatus, a bridge circuit for impressing upon said receiving apparatus desired signaling currents produced in said antenna by waves traveling in 80 a given direction, and means for preventing currents produced in said antenna by waves of a frequency near that of the desired waves and traveling in the same direction as the desired waves from being impressed 85 upon said receiving apparatus.

4. The combination in a radio receiving 90 system of an aperiodic horizontal receiving antenna, a receiving apparatus, and a bridge circuit for impressing upon said receiving 95 apparatus desired signaling currents produced in said antenna by waves traveling in a given direction, one of the arms of said bridge comprising a resonant circuit which is tuned to a different frequency from that 100 of the desired waves for preventing currents produced in said antenna by waves of a frequency near that of the desired waves and traveling in the same direction as the desired waves from being impressed upon 105 said receiving apparatus.

5. The combination in a radio receiving 110 system of an aperiodic horizontal receiving antenna, a receiving apparatus, and a bridge circuit for impressing upon said receiving 105 apparatus desired signaling currents produced in said antenna by waves traveling in a given direction, one of the arms of said bridge including two parallel resonant circuits which are tuned to two different frequencies from that of the desired waves for preventing currents produced in said antenna by waves of a frequency near that of the desired waves and traveling in the same direction as the desired waves from being 115 impressed upon said receiving apparatus.

6. The combination in a radio receiving 120 system of an aperiodic horizontal receiving antenna, a receiving apparatus, and a bridge circuit for impressing upon said receiving 125 apparatus desired signaling currents produced in said antenna by waves traveling in a given direction, one of the arms of said bridge including two parallel resonant circuits which are tuned to two different frequencies from that of the desired waves for preventing currents produced in said antenna by waves of a frequency near that of the desired waves and traveling in the same direction as the desired waves from being

impressed upon said receiving apparatus, the arm of said bridge which includes two parallel resonant circuits being so proportioned as to offer a substantially infinite impedance to currents of the desired signaling frequency.

7. The combination in a radio receiving system, of an aperiodic horizontal receiving antenna, a receiving apparatus, and a bridge circuit for impressing upon said receiving apparatus desired signaling currents produced in said antenna by waves traveling in a given direction, each of two of the arms of said bridge including two parallel circuits which are tuned to two different frequencies from that of the desired waves for preventing currents produced in said antenna by waves of a frequency near that of the desired waves and traveling in the same direction as the desired waves from being impressed upon said receiving apparatus.

8. The combination in a radio receiving system of an aperiodic horizontal receiving antenna, a receiving apparatus, and a bridge circuit for impressing upon said receiving apparatus desired signaling currents produced in said antenna by waves traveling in a given direction, each of two of the arms of said bridge including two parallel circuits which are tuned to two different frequencies from that of the desired waves for preventing currents produced in said antenna by waves of a frequency near that of the desired waves and traveling in the same direction as the desired waves from being impressed upon said receiving apparatus, each of the arms of said bridge which include two parallel resonant circuits being so proportioned as to offer a substantially infinite impedance to currents of the desired signaling frequency.

9. The combination in a radio receiving system of an aperiodic horizontal receiving antenna, a receiving apparatus, means for impressing upon said receiving apparatus desired signaling currents produced in said antenna by waves traveling in a given direction, and means for preventing currents produced in said antenna by waves of frequencies above and below that of the desired waves and traveling in the same direction as the desired waves from being impressed upon said receiving apparatus.

10. The combination in a radio receiving system of an aperiodic horizontal receiving antenna, a receiving apparatus, means for impressing upon said receiving apparatus desired signaling currents produced in said antenna by waves traveling in a given direction and a pair of resonant circuits which are tuned to two frequencies, one above and one below that of the desired waves for preventing currents produced in said antenna by waves of frequencies above and below that of the desired waves and traveling in

the same direction as the desired waves from being impressed upon said receiving apparatus.

11. The combination in a radio receiving system of an aperiodic horizontal receiving antenna, a receiving apparatus, a bridge circuit for impressing upon said receiving apparatus desired signaling currents produced in said antenna by waves traveling in a given direction; and means for preventing currents produced in said antenna by waves of frequencies above and below that of the desired waves and traveling in the same direction as the desired waves from being impressed upon said receiving apparatus. 80

12. The combination in a radio receiving system of an aperiodic horizontal receiving antenna, a receiving apparatus, a bridge circuit for impressing upon said receiving apparatus desired signaling currents produced in said antenna by waves traveling in a given direction, one of the arms of said bridge comprising two parallel resonant circuits which are tuned to two different frequencies, one above and one below that of the desired waves for preventing currents produced in said antenna by waves of frequencies above and below that of the desired waves and traveling in the same direction as the desired waves from being impressed upon said receiving apparatus. 85

13. The combination in a radio receiving system of an aperiodic horizontal receiving antenna, a receiving apparatus, and a bridge circuit for impressing upon said receiving apparatus desired signaling currents produced in said antenna by waves traveling in a given direction, one of the arms of said bridge comprising two parallel resonant circuits which are tuned to two different frequencies, one above and one below that of the desired waves for preventing currents produced in said antenna by waves of frequencies above and below that of the desired waves and traveling in the same direction as the desired waves from being impressed upon said receiving apparatus. 90

14. The combination in a radio receiving system of an aperiodic horizontal receiving antenna, a receiving apparatus, and a bridge circuit for impressing upon said receiving apparatus desired signaling currents produced in said antenna by waves traveling in a given direction, each of two of the arms of

said bridge including two parallel circuits which are tuned to two different frequencies, one above and one below that of the desired waves for preventing currents produced in said antenna by waves of frequencies above and below that of the desired waves and traveling in the same direction 130

as the desired waves from being impressed upon said receiving apparatus.

15. The combination in a radio receiving system of an aperiodic horizontal receiving antenna, a receiving apparatus, and a bridge circuit for impressing upon said receiving apparatus desired signaling currents produced in said antenna by waves traveling in a given direction, each of two of the arms 10 of said bridge including two parallel circuits which are tuned to two different frequencies, one above and one below that of the desired waves for preventing currents produced in said antenna by waves of frequencies above and below that of the desired waves and traveling in the same direction as the desired waves from being impressed upon said receiving apparatus, each of the 15 two arms of said bridge which includes two parallel resonant circuits being so proportioned as to offer a substantially infinite impedance to currents of the desired signaling frequency.

16. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, means for impressing upon said receiving apparatus currents flowing in opposite directions in the two wires of said antenna, 30 and means for preventing currents produced in said antenna by waves of a frequency near that of the desired waves and traveling in the same direction as the desired waves from being impressed upon said receiving apparatus.

17. The combination in a radio receiving system of an aperiodic receiving antenna which is grounded at both ends and which comprises a pair of parallel horizontal wires, 45 means for causing currents produced in said antenna by waves coming from a desired direction to flow in opposite directions through the two wires thereof, a receiving apparatus, means for impressing upon said receiving apparatus currents flowing in opposite directions in the two wires of said antenna, and a resonant circuit which is tuned to a different frequency from that of the desired waves for preventing currents produced in 50 said antenna by waves of a frequency near that of the desired waves and traveling in the same direction as the desired waves from being impressed upon said receiving apparatus.

60 18. The combination in a radio receiving system of an aperiodic receiving antenna which is grounded at both ends and which comprises a pair of parallel horizontal wires, means for causing currents produced in said antenna by waves coming from a desired di-

rection to flow in opposite directions through the two wires thereof, a receiving apparatus, a bridge circuit for impressing upon said receiving apparatus currents flowing in opposite directions in the two wires of said antenna, and means for preventing currents produced in said antenna by waves of a frequency near that of the desired waves and traveling in the same direction as the desired waves from being impressed upon said receiving apparatus. 70 75

19. The combination in a radio receiving system of an aperiodic receiving antenna which is grounded at both ends and which comprises a pair of parallel horizontal wires, 80 means for causing currents produced in said antenna by waves coming from a desired direction to flow in opposite directions through the two wires thereof, a receiving apparatus and a bridge circuit for impressing upon said receiving apparatus currents flowing in opposite directions in the two wires of said antenna, one of the arms of said bridge comprising a resonant circuit which is tuned to a different frequency from that of the desired waves for preventing currents produced in said antenna by waves of a frequency near that of the desired waves and traveling in the same direction as the desired waves from being impressed upon said 85 receiving apparatus. 90 95

20. The combination in a radio receiving system of an aperiodic receiving antenna which is grounded at both ends and which comprises a pair of parallel horizontal wires, 100 means for causing currents produced in said antenna by waves coming from a desired direction to flow in opposite directions through the two wires thereof, a receiving apparatus and a bridge circuit for impressing upon said 105 receiving apparatus currents flowing in opposite directions in the two wires of said antenna, one of the arms of said bridge including two parallel resonant circuits which are tuned to two different frequencies from 110 that of the desired waves for preventing currents produced in said antenna by waves of a frequency near that of the desired waves and traveling in the same direction as the desired waves from being impressed upon 115 said receiving apparatus.

21. The combination in a radio receiving system of an aperiodic receiving antenna which is grounded at both ends and which comprises a pair of parallel horizontal wires, 120 means for causing currents produced in said antenna by waves coming from a desired direction to flow in opposite directions through the two wires thereof, a receiving apparatus, and a bridge circuit for impressing upon 125 said receiving apparatus currents flowing in opposite directions in the two wires of said antenna, one of the arms of said bridge including two parallel resonant circuits which are tuned to two different frequencies 130

from that of the desired waves for preventing currents produced in said antenna by waves of a frequency near that of the desired waves and traveling in the same direction as the desired waves from being impressed upon said receiving apparatus, the arm of said bridge which includes two parallel resonant circuits being so proportioned as to offer a substantially infinite impedance to currents of the desired signaling frequency.

22. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit for impressing upon said receiving apparatus currents flowing in opposite directions in the two wires of said antenna, each of two of the arms of said bridge including two parallel resonant circuits which are tuned to two different frequencies from that of the desired waves for preventing currents produced in said antenna by waves of a frequency near that of the desired waves and traveling in the same direction as the desired waves from being impressed upon said receiving apparatus.

23. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit for impressing upon said receiving apparatus currents flowing in opposite directions in the two wires of said antenna, each of two of the arms of said bridge including two parallel resonant circuits which are tuned to two different frequencies from that of the desired waves for preventing currents produced in said antenna by waves of a frequency near that of the desired waves and traveling in the same direction as the desired waves from being impressed upon said receiving apparatus, each of the arms of said bridge which include two parallel resonant circuits being so proportioned as to offer a substantially infinite impedance to currents of the desired signaling frequency.

24. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, means for impressing upon said

receiving apparatus currents flowing in opposite directions in the two wires of said antenna, and means for preventing currents produced in said antenna by waves of frequencies above and below that of the desired waves and traveling in the same direction as the desired waves from being impressed upon said receiving apparatus.

25. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, means for impressing upon said receiving apparatus currents flowing in opposite directions in the two wires of said antenna, and a pair of resonant circuits which are tuned to two frequencies, one above and one below that of the desired wave for preventing currents produced in said antenna by waves of frequencies above and below that of the desired waves and traveling in the same direction as the desired waves from being impressed upon the receiving apparatus.

26. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, a bridge circuit connected to the two wires of said antenna for impressing upon said receiving apparatus currents flowing in opposite directions in the two wires of said antenna, and means for preventing currents produced in said antenna by waves of frequencies above and below that of the desired waves and traveling in the same direction as the desired waves from being impressed upon said receiving apparatus.

27. The combination in a radio receiving system of an aperiodic receiving antenna, which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, one of the arms of said bridge comprising two parallel resonant circuits which are tuned to two different frequencies, one above and one below that of the desired waves for preventing currents produced in said antenna by waves of frequencies above and below that of the

desired waves and traveling in the same direction as the desired waves from being impressed upon said receiving apparatus.

28. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, one of the arms of said bridge comprising two parallel resonant circuits which are tuned to two different frequencies, one above and one below that of the desired waves and traveling in the same direction as the desired waves from being impressed upon said receiving apparatus.

29. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, each of two of the arms of said bridge comprising two parallel resonant circuits which are tuned to two different frequencies, one above and one below that of the desired waves and traveling in the same direction as the desired waves from being impressed upon said receiving apparatus, the arm of said bridge which includes the parallel resonant circuits being so proportioned as to offer a substantially infinite impedance to currents of the desired signaling frequency.

30. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, each of two of the arms of said bridge comprising two parallel resonant circuits which are tuned to two different frequencies, one above and one below that of the desired waves and traveling in the same direction as the desired waves from being impressed upon said receiving apparatus, the arm of said bridge which includes the parallel resonant circuits being so proportioned as to offer a substantially infinite impedance to currents of the desired signaling frequency.

31. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, each of two of the arms of said bridge comprising two parallel resonant circuits which are tuned to two different frequencies, one above and one below that of the desired waves and traveling in the same direction as the desired waves from being impressed upon said receiving apparatus.

32. The combination in a radio receiving system of an aperiodic receiving antenna which is grounded at both ends and which comprises a pair of parallel horizontal wires, means for causing currents produced in said antenna by waves coming from a desired direction to flow in opposite directions through the two wires thereof, a receiving apparatus, and a bridge circuit connected to the two wires of said antenna for impressing upon said receiving apparatus currents flowing in opposite directions in the two wires of said antenna, each of two of the arms of said bridge comprising two parallel resonant circuits which are tuned to two different frequencies, one above and one below that of the desired waves and traveling in the same direction as the desired waves from being impressed upon said receiving apparatus, the arm of said bridge which includes the parallel resonant circuits being so proportioned as to offer a substantially infinite impedance to currents of the desired signaling frequency.

In witness whereof, I have hereunto set my hand this 23rd day of May, 1921.

HAROLD H. BEVERAGE.
